UNITED STATES PATENT OFFICE.

THOMAS ALFRED JONES, OF RIDGWAY, ILLINOIS.

STORM-COAT.

SPECIFICATION forming part of Letters Patent No. 758,182, dated April 26, 1904.

Application filed February 17, 1904. Serial No. 194,082. (No model.)

To all whom it may concern:

Be it known that I, THOMAS ALFRED JONES, a citizen of the United States, residing at Ridgway, in the county of Gallatin and State of Illinois, have invented a new and useful Storm-Coat, of which the following is a specification.

This invention relates to overcoats or storm-coats more particularly of waterproof character, and has for its object to provide a simply-constructed garment of the class referred to which will effectually protect the undergarments from rain or snow, no matter how violently the arms or person of the wearer may be required to move about.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a view of one of the improved garments particularly disconnected. Fig. 2 is a similar view with the parts wholly connected and fastened.

The body 10 of the garment is formed in the usual manner with sleeves 11 12 and neck-openings 13 and may be provided with the usual folding collar 14, if required. The material may be of any of the usual fabrics employed in such garments, but will preferably be of waterproof character.

The improvements to the garment consist first in extending one of the fronts laterally, as at 16, with its free edge 17 near the center

of the opposite side, or substantially in vertical alinement with the opposite sleeve, and provided with suitable fastening means, such as buttons 18 and buttonholes 19.

The improvement further consists in a flap 55 20, extending along the center of the shoulder-line at 21 and around the front portion of the garment at the juncture of the adjacent sleeve and the body of the garment, as at 22, and forming a pocket-like receptacle to receive the outer upper corner of the lateral extension 16, and the improvement consists, furthermore, in providing a cover-flap 23, attached along the center of the shoulder-line between the neck-opening and the juncture 65 of the sleeve and garment-body and forming a covering means to fold over the upper portion of the flap 20 and adjacent upper portion of the extension portion 16. The flap 23 will be provided with suitable fastening means, such as buttonholes 24, for engagement with buttons 25 on the extension portion 16, and, if required, a button may also be attached to the pocket-flap 20 for engagement with a corresponding buttonhole in the flap 23. By 70 this simple arrangement it will be obvious that a simply-constructed and easily-applied garment is produced which will effectually exclude rain or snow and thoroughly protect the undergarments, while at the same time 80 leaving the sleeves free to be moved about to any required extent by the action of the arms of the wearer.

The garment will be especially useful for persons in driving or following other pursuits 85 which require them to use the arms more or less violently while wearing the garment.

The expense over an ordinarily-constructed garment is comparatively small and will not be considered when the material advantages 90 are taken into account.

The garment thus constructed may be of any required material and any required style of "cut" and may be worn by children or adults with equal facility.

If required, the under flap of the front at one side may be cut away, as indicated by dotted line 26 in Fig. 1, to reduce the thickness at the front of the "skirt" of the garment.

Having thus described the invention, what is claimed is—

A storm-coat having one side of the front extended laterally over the other side, a flap 5 extending along the top of the shoulder and along the juncture of the sleeve and the body of the garment and forming a pocket-like receptacle for the adjacent portion of said extended front, and a flap extending along the 10 top of the shoulder and forming a cover for

the contiguous portions of said extended front and of said receptacle-forming flap.

In testimony that I claim the foregoing as my own I have hereto affixed my signature in the presence of two witnesses.

THOMAS ALFRED JONES.
